UNITED STATES PATENT OFFICE.

THEODORE A. DODGE, OF BROOKLINE, MASSACHUSETTS.

MACHINE FOR MANUFACTURING BOTTLE-COVERS.

SPECIFICATION forming part of Letters Patent No. 336,097, dated February 16, 1886.

Application filed August 20, 1885. Serial No. 174,920. (No model.)

To all whom it may concern:

Be it known that I, THEODORE A. DODGE, of Brookline, county of Norfolk, and State of Massachusetts, have invented an Improvement 5 in Machines for Manufacturing Bottle-Covers, of which the following description, in connection with the accompanying drawings, is a specification, like letters on the drawings representing like parts.

This invention has for its object the production of a machine by which to manufacture bottle-covers from paper.

My invention consists, essentially, in the combination, with a guide to fold a strip of 15 material into tubular form, and stitch-forming mechanism to unite the said tube, of feeding and cutting mechanism to feed the said tube and to cut it into lengths suitable for covers.

Figure 1 is an elevation of a machine embodying my invention; Fig. 2, in vertical cross-section, shows the cutting mechanism which I have added to the stitch-forming mechanism, and also a horizontal section of the said rolls in the dotted line x x ; and Fig. 3 shows a bottle-cover complete.

Referring to the drawings, the bed-plate a , the main-shaft c , the head i , the cams t and w^2 , the lever v^2 , the link u^2 , the pawl-lever s^2 , the pawl t^2 , the shafts o^2 p^2 , their attaching feeding-rolls q^2 r^2 , the lever e^2 , the link d^2 , the shaft b^2 , the arm a^2 , for actuating the rack-bar to 30 oscillate the usual whirl (not shown,) the work-supporting arm g^2 , partially surrounded by the long grooved guide h^2 , the latterlapping 35 or folding the material in tubular form about the frame g^2 , the presser-bar s and presser-foot l , the needle-bar k , the hooked-needle m , the cast-off bar n , and the cast-off j are all substantially as in the United States Patent

40 No. 146,948, granted January 28, 1874, to E. P. Richardson, to which patent reference may be had, the said mechanism being herein employed to stitch or unite paper to form tubes to be made into bottle-covers. The feeding-

45 rolls q^2 r^2 draw the material from the stitching mechanism and pass it in tubular form between the cutting mechanism herein shown, as cylinders A B , the former provided with a transverse cutting-blade, A' , and the latter 50 with a transverse slot, B^2 , the said cutting mechanism, as herein shown, flattening the tube T and severing the same transversely,

the circumference of the said rolls being substantially equal to the length of the bottle-cover to be made. The shaft of the cylinder 55 B has fast upon it the gear B' , which is engaged and rotated by the intermediate B^3 , which derives its motion from the toothed gear r^3 , common to said patent, and fast on the shaft p^2 . The shaft of the cylinder A is rotated by the gear B' , which engages the gear A^2 , so that the two cylinders move in unison, the surface-speed of the said cylinders and of the rolls q^2 r^2 being the same. The cylinder 60 A , is provided with two cutting-blades, D , at 65 right angles to the blade A' , (see Fig. 2,) which blades enter grooves B^4 at right angles to but intersecting the groove B^2 , the said blades D cutting longitudinal slots 2 2 at one end of the bottle-cover tube T to enable that end of the 70 tube to be closed squarely.

Referring to Fig. 3, the stitch uniting the paper into a tube is shown at 4; but instead of the chain-stitch mechanism of the machine herein shown I might employ any other well-known stitch-forming mechanism in connection with a folding-guide arranged in front thereof and with a tube feeding and cutting mechanism arranged rearward thereof.

The material to be used for the manufacture 80 of bottle-covers will preferably be thick paper, embossed or indented at intervals so as to form projections and leave depressions to give softness and elasticity to the paper. The paper used will be formed into a tube by passing the 85 same between the guide h^2 and the arm g , as described in the said patent, the paper strip introduced in flat or nearly flat condition being folded into tubular form with its edges overlapped, as or before it arrives in position 90 under the bar k , to be united by the stitch or fastening used.

Having described a mechanism by which to practice my invention, I desire it to be understood that instead of the particular stitch-forming mechanism shown, I may employ any other stitch-forming mechanism commonly used for stitching hose or tubing; and instead of the particular cutting mechanism which is common to machines for forming paper bags 95 and for cutting off paper tubes, I may use any other mechanism commonly employed in paper-bag machines by which to sever paper tubes into bag lengths, it being possible to 100

employ such other devices by but slight changes in mechanical devices to operate the cutting-off mechanism in the proper time with relation to the stitching mechanism.

5 I claim—

1. A guide to fold a strip of paper or other material into a tube and stitch-forming mechanism to unite the said material to form a tube, combined with tube-feeding and tube-
10 cutting mechanism by which to feed the said tube and cut it into short lengths, the said guide being arranged in front of the said stitch-forming mechanism, and the said feeding and cutting mechanism rearward thereof, sub-
15 stantly as described.

2. A guide to fold a strip of material into

tubular form and stitch-forming mechanism to unite the said material to form a tube, combined with tube-feeding and with tube-cutting mechanism to slit the tube longitudinally at 20 22, and to cut it off transversely, the said guide being arranged in front of the said stitch-forming mechanism, and the said feeding and cutting mechanism rearward thereof, substantially as described. 25

In testimony whereof I have signed my name to this specification in the presence of two subscribing witnesses.

THEODORE A. DODGE.
